CLAIM

The ornamental design for a hook holder cap and retractable hook to be used in hand lamp, as shown and described.

DESCRIPTION

FIG. 1 is a perspective view of a hook holder cap and retractable hook to be used in hand lamp, showing my invention;

FIG. 2 is a front elevational view of the invention;

FIG. 3 is a rear elevational view of the invention;

FIG. 4 is a left-side elevational view of the invention, the right-side elevational view being a mirror image thereof;

FIG. 5 is a top plan view of the invention; and,

FIG. 6 is another view showing the extended hook, the two circular arrows included demonstrate that the hook is rotatable.

The broken line showing of hand lamp is included for the purpose of illustrating environmental structure and forms no part of the claimed design.
